US00D622288S

(12) **United States Design Patent**
Miller et al.

(10) **Patent No.:** US D622,288 S
(45) **Date of Patent:** ** Aug. 24, 2010

(54) **VACUUM REGULATOR**

(75) Inventors: **Ronnie Joe Miller**, Overland Park, KS (US); **Steven M. Matusek**, Olathe, KS (US)

(73) Assignee: **Aeromotive, Inc.**, Lenexa, KS (US)

(**) Term: **14 Years**

(21) Appl. No.: **29/335,488**

(22) Filed: **Apr. 16, 2009**

(51) **LOC (9) Cl.** 15-01

(52) **U.S. Cl.** D15/5
